(57) **CLAIM**

The ornamental design for an case for recorded media, substantially as shown and described.

DESCRIPTION

FIG. 1 is a top perspective view of a first embodiment of a case for recorded media in a closed position;
 FIG. 2 is a top elevation view thereof;
 FIG. 3 is a front elevation view thereof;
 FIG. 4 is a bottom elevation view thereof;
 FIG. 5 is a side elevation view thereof;
 FIG. 6 is a top perspective view of a case for recorded media in an open position and inserts;
 FIG. 7 is a top elevation view thereof;
 FIG. 8 is a front elevation view thereof;
 FIG. 9 is a bottom elevation view thereof;
 FIG. 10 is a right side elevation view thereof;
 FIG. 11 is a left side elevation view thereof;
 FIG. 12 is a top perspective view thereof showing the inserts in an exploded position;
 FIG. 13 is a front elevation view thereof;
 FIG. 14 is a right elevation view thereof;
 FIG. 15 is a left elevation view thereof;
 FIG. 16 is another top perspective view thereof showing some of the inserts in an exploded position;
 FIG. 17 is a front perspective view thereof;
 FIG. 18 is a right side elevation view thereof; and,
 FIG. 19 is a left side elevation view thereof.
 The broken line portions in all views are for illustrative purposes only and form no part of the claimed design.
